UNITED STATES PATENT OFFICE.

MINOR E. CHAMBERLAIN, OF LEBANON, MISSOURI.

REINFORCED CONCRETE CONSTRUCTION.

1,167,624.

Specification of Letters Patent. Patented Jan. 11, 1916.

Application filed February 13, 1915. Serial No. 7,936

To all whom it may concern:

Be it known that I, MINOR E. CHAMBERLAIN, a citizen of the United States, residing at the city of Lebanon, county of La Cledé, and State of Missouri, have invented 5 a new and useful Reinforced Concrete Construction, of which the following is a specification.

This invention relates to reinforced concrete construction, including such structures 10 as annular or polygonal walls, solid monolithic bodies such as posts and the like, and all other structures composed of concrete which may be erected or formed in accordance with the principles hereinafter explained.

An object of the invention is to provide 20 a concrete structure composed of suitable upright reinforcements spaced according to the requirements of the structure to be formed and having metallic reinforcing laths secured thereto and supporting walls or wall faces of concrete between which an open space remains, it being intended that 25 the open space between the walls may be filled with concrete so as to form a monolithic wall structure the opposite surfaces of which comprise the concrete first secured to the metallic laths.

Another object of the invention is to provide 30 a concrete wall including parallel upright reinforcing members for the outer surface of the wall, corresponding parallel upright reinforcing members for the inner surface of the wall, metallic reinforcing members uniting the outer uprights with the corresponding inner uprights, metallic laths secured to the outer and inner uprights, respectively, two separate concrete 40 wall portions embedding the outer and inner laths, respectively, and leaving an open space adapted to receive concrete whereby the inner and outer wall portions may be monolithically united, the same constituting 45 the form by which the concrete interposed between them will be held in place until it has hardened.

A further object is to provide a concrete structure comprising walls constructed as 50 above explained, in combination with transverse reinforcing elements connecting said walls and supporting reinforced concrete floor structure.

Another object is to provide an improved 55 reinforcement for posts and the like, comprising a central reinforcing member, par-

allel reinforcing members connected to the central member, metallic reinforcements extending around the series of reinforcements, and concrete embedded and supported by 60 the last-named reinforcements, and forming a central open space adapted to receive concrete or not, as desired, whereby either a hollow post or a solid monolithic post 65 may be produced, depending upon whether or not the central space is filled with concrete.

Numerous other objects and advantages 70 to be attained and accomplished by the invention will be apparent from the following description, reference being made to the accompanying drawing in which—

Figure 1 is a sectional view illustrating a portion of an annular wall of the shape ordinarily used in silos, a portion of the 75 outer and inner wall surface being monolithically united, and another wall surface being shown without the concrete filling.

Fig. 2 is a side elevation of the reinforcements before the concrete is applied thereto. Fig. 3 is a sectional view on the line 3—3 of Fig. 2. Fig. 4 is a horizontal sectional view on the line 4—4 of Fig. 3. Fig. 5 is a perspective view illustrating one of the elements by which the horizontal reinforce- 85

ments are secured to the uprights. Fig. 6 is a horizontal sectional view of a structure having a polygonal wall, and illustrating the reinforcing devices by which a concrete floor is secured in place. Fig. 7 is a sec- 90

tional view on the line 7—7 of Fig. 8. Fig. 8 is a view showing the outer and inner upright reinforcements and the devices by which they are connected, and also illustrating one of the floor reinforcements, the 95

horizontal reinforcements for the walls and floor being shown in section. Fig. 9 is a perspective view illustrating the means of securing the horizontal reinforcements to the walls and to the floor beams. Fig. 10 is 100 a sectional view illustrating the reinforce- 105

ments at the corners of the building. Fig. 11 is a perspective view of one of the outer corner reinforcements. Fig. 12 is a perspective view of a portion of one of the reinforcements for the inner corners. Fig. 13 is a sectional view of a hollow pole or post embodying the invention. Fig. 14 is a view illustrating the means by which the horizontal 110

reinforcements are secured to the vertical reinforcements. Fig. 15 is a similar view showing the horizontal reinforcements

secured in place, and also illustrating the means for connecting the adjacent ends of the horizontal reinforcing members. Fig. 16 is a perspective view of one of the corner members showing portions of the horizontal reinforcements attached thereto. Fig. 17 is a perspective view illustrating one of the members by which the central reinforcing member is connected to the corner reinforcing members. Fig. 18 is a sectional view of a portion of a post in which the space formed by the outer wall structure is filled with concrete, thus producing a solid monolithic reinforced post, this view also illustrating a different form of corner members. Fig. 19 is a side elevation of a portion of one of the corner members illustrating the horizontal reinforcements secured thereto. Fig. 20 is a sectional view on the line 20—20 of Fig. 19. Fig. 21 is a sectional view of a portion of a solid reinforced concrete post illustrating a still different corner structure. Fig. 22 is a side elevation of the corner reinforcing member embodied in Fig. 21, illustrating the horizontal reinforcements secured thereto. Fig. 23 is a sectional view on the line 23—23 of Fig. 22.

From the foregoing it will be understood that one specific embodiment of the invention as it might be employed in an annular wall, is illustrated in Figs. 1 to 5 inclusive; another specific embodiment of the invention as it might be employed in a polygonal wall, such, for instance, as the wall of a building, is illustrated in Figs. 6 to 12 inclusive; and a third specific embodiment of the invention as it might be employed in the construction of posts and poles is illustrated in Figs. 13 to 23 inclusive. It will also be understood that the particular form of corner reinforcing members illustrated in Figs. 10, 11 and 12 may be utilized with equal advantage in the construction of the posts or poles.

In describing the different specific embodiments of the invention I will describe such embodiments in the order above mentioned, it thus being necessary to make reference only to a single sheet of the drawing at any one time.

The structure illustrated in Figs. 1 to 5 inclusive, comprises an outer annular series of upright reinforcements, each comprising a single sheet folded to provide three perpendicularly disposed lateral wings, including one wing 1 of double thickness, and two wings 2 of a single thickness of the sheet. These uprights are arranged in annular series with the double wings 1 extending radially inwardly, and the wings 2 of single thickness of the series of reinforcements being in annular alinement, as will be understood by reference to Figs. 1 and 4. Certain of the wings 2 are provided with integral tongues 3 by which the horizontal sheet

metal reinforcements 4 are secured in place. Each horizontal reinforcement 4 is connected to the adjacent one in the same plane, preferably by a tongue or reduced portion 5 on one of said reinforcements passing through a slot near the end of the adjacent reinforcement and then being bent back in clamping position, as will be understood by reference to Fig. 2. There is also an inner annular series of reinforcements, corresponding in number and position to the outer series. Each reinforcement of the inner series comprises a piece of sheet metal folded to provide three perpendicularly disposed wings, the wing 6 of which is of double thickness of the sheet and the two wings 7 of which are of single thickness of the sheet. The wings 6 are extended radially outwardly toward the wings 1 of the outer series of reinforcements, and the wings 7 of the inner series are in annular alinement. Each reinforcement of the outer series is connected to a corresponding reinforcement of the inner series by a number of reinforcing metallic connecting devices. Each connecting device comprises a pair of plates 8 attached together by suitable binding elements 9 and embracing the wings 1 and 6 between their outer and inner ends respectively. The outer ends of the plates 8 are provided with laterally extended portions 10 bearing against the wings 2 of single thickness on the outer reinforcements, and the inner ends of said plates are provided with similar lateral extensions 11 bearing against the wings 7 of single thickness on the inner reinforcements. Horizontal metallic reinforcements 12 are placed against the inner surfaces of the inner reinforcements, and may be retained in position in the same way that the reinforcements 4 are retained in position against the outer uprights. The reinforcements 4 and 12, and the connecting reinforcements 8 are further secured in position by means of suitable clamping plates 13 adapted to bear against the outer and inner surfaces of the reinforcements 4 and 12, respectively, and having tongues 14 which are passed between said reinforcements and clamped against the lateral extended portions 10 and 11, as clearly illustrated in Fig. 4. Thus the outer and inner wall reinforcements are rigidly connected and prevented from relative movement after once being placed. The reinforcements arranged in this manner are built up to a suitable height after which an outer concrete wall or wall portion 15 is formed by placing a layer of concrete against and upon the outer reinforcements so as to engage and embed the horizontal reinforcements 4, which will hold the concrete until it becomes hardened. When the concrete is applied in this manner there is no necessity for the use of a form or mold to confine the concrete, because the

concrete being in a plastic condition may be placed by means of a trowel or the like, similar to the manner that plaster walls are formed by such implements. A portion of the plastic concrete is forced into the spaces between the horizontal reinforcements, so that said reinforcements will be embedded thereby and will support the concrete until it hardens. In a similar manner an inner concrete wall or wall portion 16 is formed in connection with the inner reinforcements, the plastic concrete being applied in the same way. The concrete of which the inner wall portion is formed is also forced into the spaces between the horizontal reinforcements 12 and against the outer surfaces of said reinforcements, thus embedding said reinforcements and forming an efficient inner wall. The entire structure may thus be formed if desired, in which event the structure will be composed in an outer reinforced concrete wall 15, and an inner reinforced concrete wall 16, with an intervening space between said walls, and the rigid metallic connections 8 connecting the outer and inner walls and thus forming a rigid structure.

If found preferable in any instance the space between the outer and inner walls may be filled with concrete as shown at 17 in Fig. 1. The concrete filler 17 is placed between the outer and inner walls after the latter have hardened and form a monolithic union with the outer and inner walls. This concrete filler also embeds the metallic connections 8 which connect the outer and inner reinforcements and give rigidity to the outer and inner wall portions 15 and 16, enabling each of said wall portions to strengthen and support the other. As a result of this arrangement the outer and inner wall portions 15 and 16 will retain the concrete which is placed therebetween as a filler while the filler is forming a monolithic union with said outer and inner walls. In this way the necessity for the use of forms or molds to retain the concrete and to shape the wall surfaces is dispensed with, the metallic reinforcements holding the concrete of which the outer and inner walls are formed until said concrete becomes thoroughly hardened, after which the outer and inner walls serve to confine the concrete composing the filler. It is obvious that walls may be thus formed of any desired shape whether annular as illustrated in Fig. 1, or polygonal as hereinafter explained. A structure of this character is especially adapted for use as a silo, and may be conveniently erected at any place without the necessity of providing cumbersome and expensive forms or molds, the plastic concrete being placed upon the outer and inner reinforcements in a well understood manner without the necessity of special training for such purpose.

In Figs. 6 to 12 I have illustrated the invention embodied in a polygonal structure having a reinforced concrete floor formed in monolithic union with the walls. As illustrated the walls comprise outer upright reinforcements and inner upright reinforcements. These upright reinforcements are similar to the reinforcements previously described, each outer reinforcement being composed of sheet metal folded to provide three perpendicularly disposed wings, of which the wing 18 is of double thickness, and the two wings 19 are of single thickness of the sheet. The inner upright reinforcements are also composed of sheet metal each comprising a sheet folded to provide three perpendicularly disposed lateral wings, of which the wing 20 is of double thickness and the two wings 21 are of single thickness of the sheet. The outer and inner upright reinforcements are placed a suitable distance apart with the wings 18 and 20 of double thickness extending toward each other and connected by metallic reinforcing members each of which includes two plates 22 embracing the wings 18 and 20 between their ends and provided with lateral extensions 23. These plates 22 are secured together by cutting or stamping therefrom tongues 24 from one plate which are pressed through 95 similarly shaped holes in the other plate and thereby fastening two plates together. The lateral extensions 23 press against the lateral wings 19 and 21. The outer and inner upright reinforcements support a plurality of 100 horizontal reinforcements 25 retained in position by tongues 26 and by plates 27 having extensions 28 extending between said reinforcements 25 and clamping upon the inner surface of the wings 19 and 21 of single 105 thickness. The tongues 28 also clamp upon the lateral extensions 23, thus firmly connecting the outer and inner reinforcements so that each will afford strength to the other. In the outer corner reinforcing members the wings 19 of single thickness are formed at 110 right angles to each other which will be understood by reference to Figs. 10 and 11. In the inner reinforcing members the wings 21 of single thickness are also formed at 115 right angles to each other, and in planes parallel with the planes of the wings 19 of the outer corner members. The wings 18 and 20 of the corner reinforcements are connected by reinforcing members 29 similar 120 to the reinforcing member 22 with the exception that said members 29 are not provided with lateral extensions on their extremities. The wings 19 at the corners are preferably provided with tongues 30 adapted 125 to receive and support the horizontal reinforcements 25 which pass around the corners, and the wings 21 of the inner corner members are also preferably formed with tongues 31 for the purpose of supporting 13.

the inner horizontal reinforcements 25 at the corners. In this way there is formed an outer series of upright reinforcements and a coöperating inner series of upright reinforcements, each series of uprights supporting a series of horizontal reinforcements 25. The inner series of reinforcements and the outer series of reinforcements are retained rigidly in their proper relative adjustments by the connecting plates 22.

10 After the outer and inner reinforcements have been built up to a desired height an outer concrete wall portion 32 is formed by embedding the outer reinforcements in concrete applied by some suitable implement, such as a trowel. Similarly an inner concrete wall portion 33 is formed by embedding the inner reinforcements in concrete applied thereto by means of a trowel or otherwise, and the outer and inner walls thus formed are permitted to harden after which the intervening space is filled with a filler 34 of concrete which forms a monolithic union between the outer and inner walls placed 15 and formed in a preceding operation. A reinforced concrete floor may also be formed in monolithic union with the walls when desired. The reinforcements for the floor have their ends embedded in the wall structure, 20 and include a series of transverse reinforcing members which support an additional series of reinforcements. Each transverse reinforcing member comprises two metallic plates 35 placed side by side and having 25 their lower edges extended laterally to form wings 36 and their upper edges also extended laterally to form wings 37. Said plates are fastened together by stamping tongues 38 from one of said plates and extending 30 said tongues through corresponding holes in the adjacent plate and then clamping the tongues upon the adjacent plate. The reinforcing members 35 are supported upon the upper ends of the wings 21 on the inner 35 reinforcements, the wings 20 of the inner reinforcements as well as the wings 18 of the outer reinforcements extending between the plates 35, thus preventing lateral displacement of said plates and supporting them 40 rigidly in their proper adjustments. The plates thus formed extend from wall to wall as illustrated in Fig. 6, and other series of upright reinforcements rise above said plates 35 having their wings of double thickness 45 extending between said plates as indicated at 39 (Fig. 8). A series of horizontal reinforcements 40 is secured to the lower flanges 36 of the plates 35 by means of tongues 41 on said plates 35, and clamping plates 43 which 50 press against the reinforcements 40 and which have extensions 43 extending between the reinforcements 40 and clamping upon the flanges 36. After the reinforcements 40 have been thus secured in position a layer 55 of concrete is applied thereto by trowel

or otherwise, said concrete engaging and embedding the reinforcements 40 and the lower flanges 36 of the plates 35. The concrete thus applied to and embedding the reinforcements 40 is illustrated in the portion A of Fig. 6, while no concrete has been applied to the portions B. After the concrete applied in this manner has become hardened additional quantities of concrete are placed above the same and permitted to form a 60 monolithic union therewith until the spaces between the reinforcing plates 35 have been filled with the desired quantity of concrete as illustrated in the spaces C in Fig. 6. In this way the building may be constructed to any desired altitude and floors may be provided as needed. The floors thus constructed merge integrally with the walls, so that there is really no line of separation between the floors and walls when the building is completed.

Referring next to the structure illustrated in Figs. 13 to 23 inclusive, it will be noted that this structure includes a central reinforcement composed of sheet metal folded to provide four perpendicularly disposed lateral wings, of which the wings 44 are of double thickness and the wings 45 are of single thickness of the sheet. There are also four corner reinforcements each of which comprises a single sheet folded to provide three perpendicularly disposed lateral wings, of which the wing 46 is of double thickness and the wing 47 of single thickness of the sheet. In this particular form the corner reinforcements are connected with the central reinforcements by a number of metallic plates 48 each of which is doubled upon itself and having its double portion engaged by the arms 46 of double thickness on the corner reinforcements. The inner extremities of the plates 48 are clamped upon the arms of the central reinforcements and secured thereto by suitable fastening devices 49. A series of horizontal reinforcements 50 are supported by the corner reinforcements by means of tongues 51 formed on the corners and embracing the parts 50 whereby the latter are clamped against the uprights. The adjacent ends of the parts 50 are fastened by a tongue 52 on one of said members extending through a slot in the adjacent end of the next or the same member and clamped so as to hold the parts in proper arrangement. After the reinforcements have been thus arranged a concrete wall 53 is formed by embedding the horizontal reinforcements 50 in concrete and permitting the same to harden or solidify. After the concrete wall 50 has been formed the space inclosed thereby may be filled with concrete as will be understood by reference to Figs. 18 and 21, the concrete filler forming an integral union with the outer wall so that the completed structure has an integral concrete body having em-

bedded therein the reinforcements as described.

Figs. 18, 19 and 20 illustrate a modified form of corner reinforcements. In this structure the central reinforcements 54 are the same as that illustrated in Fig. 13. Each corner reinforcement comprises a sheet folded to provide three perpendicularly disposed wings, of which the wing 55 is of double thickness and the wings 56 are of single thickness of the sheet. Metallic plates 57 connect the wings of the central reinforcement 54 with the wings 55, the latter being extended toward the center and presenting the wings 56 outwardly for supporting the horizontal reinforcements 50 which are held against the wings 56 by tongues 57 and plates 58. The plates 58 have extensions 59 extending between the reinforcements 50 and clamping upon the wings 56, as illustrated in Fig. 20. The concrete wall surface 53 in this embodiment is applied in the same manner as the concrete forming the wall 53 illustrated in Fig. 13, and after the wall has been formed the space is filled with concrete so as to form a monolithic reinforced body.

In Figs. 21, 22 and 23 the central reinforcement 59 is the same as that illustrated in Fig. 13. The corner reinforcements comprise a sheet bent substantially in the form of an I-beam forming two arms 60 of double thickness and at right angles thereto, an arm 61 also of double thickness of the sheet, 35 and two arms 62 of single thickness of the sheet. In this structure the radial reinforcing plates 63 are the same as the plates 48, the double edges of said plates extending between the walls of the double arms 61 40 of the corner reinforcements. The horizontal reinforcements 50 in this embodiment are supported by tongues 64, and by plates 65, the latter having projections 66 extending between the plates 50 and clamping upon 45 the wings 60 of double thickness. After the horizontal reinforcements have been secured in position in this manner the outer concrete wall 53 is formed by applying concrete to the reinforcements so as to embed 50 the same therein and permitting the concrete to harden. After the concrete has hardened and formed the confining outer walls the space inclosed by said walls is filled with concrete so as to form an integral 55 or monolithic union with the inclosing walls, thus providing a solid reinforced concrete post or body.

It will be understood that there may be variations in the construction and arrangement of the parts comprising the invention without departure from the spirit thereof.

What I claim and desire to secure by Letters Patent is:

1. In a reinforced concrete structure, an outer series of upright sheet metal rein-

forcements each comprising a single sheet folded to provide three perpendicularly disposed lateral wings, one of which wings is of a double and the remaining two of a single thickness of the sheet, the single wings of the series being arranged in alinement and the double wings extending inwardly, means for supporting connecting devices on said wings of single thickness, an inner series of upright sheet metal reinforcements each comprising a single sheet folded to provide three perpendicularly disposed lateral wings, one of which wings is of a double and the remaining two of a single thickness of the sheet, the single wings of the series being arranged in alinement and adapted to support the connecting devices, and the double wings extending outwardly toward the double wings of the outer series, metallic elements engaging the wings of double thickness of both series of upright reinforcements, lateral extensions on said elements abutting against the wings of single thickness on both series of upright reinforcements, and devices binding said extensions in engagement with said wings of single thickness.

2. In a reinforced concrete structure, an outer series of upright reinforcements each comprising a single sheet of metal folded to provide three perpendicularly disposed lateral wings, one of which wings is of a double and the remaining two of a single thickness of the sheet, the wings of single thickness being adapted to support the connecting devices, and the wings of double thickness extending inwardly, an inner series of upright reinforcements each comprising a single metallic sheet folded to provide three perpendicularly disposed lateral wings, one of which is of a double thickness and the remaining two of a single thickness of the sheet, the wings of single thickness being adapted to support the connecting devices, and the wings of double thickness extending outwardly toward the wings of double thickness of the outer series of uprights, metallic elements connecting the wings of double thickness of the outer series of uprights with the wings of double thickness of the inner series of uprights, lateral extensions on said elements bearing against the wings of single thickness on both series of uprights and metallic members holding said elements in engagement with said uprights.

3. In a reinforced concrete structure, an outer series of upright reinforcements each comprising a single metallic sheet folded to provide three perpendicularly disposed lateral wings, one of which wings is of a double thickness and the remaining two of a single thickness of the sheet, the single wings being arranged in alinement, an inner series of upright reinforcements each com-

- prising a single metallic sheet folded to provide three perpendicularly disposed lateral wings, one of which wings is of a double thickness extending toward the wings of double thickness of the outer series of reinforcements, metallic elements connecting the wings of double thickness of the outer series of uprights with the wings of the inner series, and floor supporting members seated upon the ends of the wings of single thickness of the inner series of uprights and having spaces receiving the wings of double thickness of both series of uprights, whereby said members and said uprights are interlocked.
4. In a reinforced concrete structure, an outer series of upright reinforcements each comprising a single metallic sheet folded to provide three perpendicularly disposed lateral wings, one of which wings is of double thickness of the sheet, an inner series of upright reinforcements each comprising a single metallic sheet folded to provide three perpendicularly disposed lateral wings, one of which wings extends toward the wings of double thickness of the outer series of reinforcements, floor members seated upon the ends of the wings of single thickness of the inner series of uprights and having spaces receiving the wings of the outer series of uprights, and interlocking connection between the inner series of uprights and said members.
5. In a reinforced concrete structure, a series of upright sheet metal reinforcements each comprising a metallic sheet folded to provide three perpendicularly disposed lateral wings, one of which wings is of a double thickness and the remaining two of a single thickness of the sheet, a number of metallic plates for each of said reinforcements having their outer ends connected to the wing of double thickness for holding said reinforcements from inward or outward movement, means for holding said plates in rigid position to prevent inward or outward movement of said reinforcements, horizontal reinforcements encircling said series of upright reinforcements, and elements holding said horizontal reinforcements in engagement with said upright reinforcements.
6. In a reinforced concrete structure, a series of upright sheet metal reinforcements each comprising a single metallic sheet folded to provide three perpendicularly disposed lateral wings, one of which wings is of a double thickness and the remaining two of a single thickness of the sheet, a number of metallic plates engaging the wings of double thickness of said reinforcements respectively, means for holding said plates in rigid position effectively to prevent inward or outward movement of said reinforcements, a series of horizontal reinforcements encircling said series of upright reinforcements, and clamping tongues integral with said upright reinforcements engaging and holding said horizontal reinforcements in connection therewith.

In witnesses whereof, I have signed this specification in the presence of two subscribing witnesses.

MINOR E. CHAMBERLAIN.
